METAL WORKING

Claus L. Sperck, Cincinnati, Ohio, assignor to The Lodge & Shipley Company, Cincinnati, Ohio, a corporation of Ohio

Filed May 22, 1959, Ser. No. 815,153
18 Claims. (Cl. 80—13)

This invention relates to the art of metal working and in particular relates to methods and apparatus for forming hollow, generally cylindrically-shaped articles from sheet metal blanks.

The invention is concerned with the making of elongated, cylindrically-shaped articles having use in a wide variety of industrial and military applications, particularly where high strength, light weight and precise dimensions are mandatory. For example, cylinders made in accordance with the invention may be used as storage and control tanks, particularly in the chemical and food processing industry. As to military use, the articles formed by the methods of the invention are ideally suited for components of rockets and missiles such as fuel containers, skin parts, body structural members and the like.

Components such as mentioned above for rockets and missiles may have dimensions in the order of the following: length: 100"-500"; thickness: .010"-1 1/4"; diameter: 20"-150". Such components are made by the familiar wrapping and welding techniques where a flat blank of rolled steel is formed into cylindrical shape, welded at the abutting edges and then machined to dimensions. These techniques have several disadvantages. For example, where the component is to be of substantial length, it is necessary to form several like objects and then weld the adjacent ends. With such procedure it is very difficult to match diameters and to maintain all of the parts coaxial so that the wall of the part is truly symmetrical with respect to the axis. Complex and costly machining operations are required to maintain dimensions. Furthermore, the making of large parts by these techniques ordinarily requires heat treatment after welding or machining which often can lead to undesirable distortions. Where high strength is desired, the thickness of the material must be disproportionately large which adds to the total weight and is wholly undesirable in airborne devices. The outer skin of a ballistic missile should be axially true as otherwise errors may arise in the desired trajectory, and for fuel containers for rockets it is imperative that the inside dimensions be accurately controlled in order that the desired rate of burning will take place. Conventional wrapping and welding techniques do not lend themselves to the obtaining of these desired characteristics.

Besides the wrapping-welding-machining techniques mentioned above, cylinders and tubes have been made by the use of roller and spindle methods wherein a blank is supported on a spindle or a mandrel and while the spindle and blank are rotating, one or more rollers engage the blank and with relative axial motion as between the roller and the blank, the wall of the blank is reduced in thickness and elongated. In some instances the blank has a closed end which is held in abutting relationship with the end of the spindle and the relative axial motion of the roller with respect to the blank is in a direction away from the closed end, the reduced part of the blank extruding along the spindle under the action of the roller so as to completely be formed on the spindle. In other instances the blank is supported on the spindle and moved axially into the rollers or, conversely, the rollers are moved along the blank (with one end of the blank being held fixed); in either case the relative axial motion of the roller with respect to the blank being such that the working forces are taken through the unworked portion of the

2

blank and the blank extrudes off the end of the spindle. In still other instances the rollers are positively driven and also oriented with respect to the spindle so that the blank and spindle are pulled between the rollers for the reducing operation.

These methods have not been used heretofore for the forming of articles of the kind in question because of several basic difficulties.

Many of the above-mentioned techniques contemplate that the blank be hot rolled. While hot rolling has many desirable advantages, it has the distinct disadvantage of not producing strain hardening, and strain hardening is highly desirable in articles of the kind under consideration because of the attendant improvements in strength properties.

The most significant disadvantage, however, lies in the failure of these techniques to provide for dimensional accuracy, particularly with regard to wall thickness and inside diameter. The processes of the kind mentioned above, at least insofar as I am aware, contemplate that the blank or the formed part expand or open up after it leaves the rollers. In other words, present processes do not provide that each axial increment of the finished part have the same wall thickness and the same inside diameter as existed at the time of its reduction. This has the effect of making it impossible to hold close and uniform tolerances in diameter, wall thickness and axial concentricity of the finished part. Furthermore, those processes contemplating the forming of the part completely on the spindle are of little value for making articles of substantial length and diameter because of the practical difficulties in making the required size spindle.

With the above in mind then, the present invention contemplates methods and equipment for the forming of elongated, cylindrically-shaped articles by way of roller and spindle means but which are constructed and operated to eliminate the disadvantages of the spindle-roller and the wrapping and welding techniques mentioned above and to provide features and advantages which are not present in and indeed are impossible to obtain with such conventional techniques.

It is one object of the invention to provide roller and spindle apparatus and methods for using the same for the production of elongated, cylindrically-shaped articles having extremely high dimensional accuracy, both as to wall thickness and inside and outside diameter and axial concentricity.

Another object of the invention is to provide roller and spindle apparatus and methods of using the same for the production of elongated, generally cylindrically-shaped articles having extremely high strength properties as compared to those of the initial starting blank and which have a very high degree of dimensional accuracy.

Another object of the invention is to provide roller and spindle apparatus and methods of using the same for the production of elongated, generally cylindrically-shaped articles having very high strength properties yet with a minimum of weight and a high order of dimensional accuracy.

Another object of the invention is to provide roller and spindle apparatus and methods of using the same for the production of elongated, generally cylindrically-shaped articles having a very high length-to-diameter ratio and with a minimum wall thickness; for example, a length in the order of 13', a diameter just less than 3' and with a wall thickness of less than $\frac{1}{16}$ ", yet possessing dimensional accuracy and high strength.

For obtaining the foregoing objectives together with other objectives which will presently appear, the invention contemplates roller-spindle means constructed and used according to the discovery that dimensional ac-

curacy is principally a function of extrusion rate and that extrusion rate can be desirably controlled by simultaneously reducing the discrete fractional proportions of the blank. The principal control factors for accomplishing the foregoing are the number and extent of the fractional reductions, the initial feed rate of the blank and the rotational speed of the blank, all of these being coordinated to produce the desired result and the exact relationship of these factors depending upon the kind of material being worked.

In one aspect the invention contemplates the forming of elongated, cylindrically-shaped articles by simultaneously reducing and extruding discrete radial and axially-spaced portions of the wall of a cylindrically-shaped blank and controlling the extrusion rates so that the extrusion rate of the finally-reduced portion is such that each increment of the formed article has the same inside diameter and wall thickness as existed at the final reduction.

In another aspect the invention contemplates the forming of a cylindrically-shaped article by the elongation and reduction of a blank by a roller cooperating with a spindle, the roller having a plurality of rolling sections serially spaced along the axis of the blank with each working surface taking a fractional proportion of the total desired reduction and with the blank feed rate, the rotation speed of the blank and the number and extent of the reductions being correlated to control the extrusion rate of the final reduction.

Another aspect of the invention contemplates the forming of axially dimensioned, elongated, generally cylindrically-shaped articles by spindle and roller means, the roller comprising a plurality of rolling sections simultaneously operating on the blank to reduce discrete portions and move the same at different extrusion rates so that the final extrusion rate is such that the formed blank has a uniform wall thickness the same as the spacing between the spindle surface and the final roller and a uniform inside diameter which is the same as the outside diameter of the spindle.

In another aspect the invention contemplates the forming of accurately dimensioned, elongated, cylindrically-shaped articles by way of a spindle and roller means having a plurality of rolling sections which are serially spaced along the axis of the blank and each being located at a different radial distance from the axis of the blank so that each rolling section effects a fractional proportion of the total reduction required and operates simultaneously with the other sections and determining the final extrusion rate by controlling the spindle speed, the blank feed rate and the number of reductions.

The foregoing may be obtained by several different forms of equipment but it is essential that such equipment have certain basic characteristics. One of the most important of these is the construction of the roller which provides for the simultaneous reduction and elongation of discrete portions of the blank. Another is that the equipment must provide for the control of the blank feed rate and the blank rotational speed and it is preferred that such control be variable in nature so that the equipment is adaptable for a variety of different materials and blanks of varying sizes.

According to the invention, the preferred form of roller has a plurality of rolling sections, all of which are mounted on a common rotational axis and all have the same diameter and are held in closely abutting relationship with one another. Further, the invention contemplates that the roller be mounted so that it is tiltable with respect to the rotational axis of the blank, the several rolling sections and the tilting being coordinated so that the roller may be positioned with each of the rolling sections located at a different radial distance from the rotational axis of the spindle and serially spaced along the axis of the blank. This permits each of the rolling

sections to perform its work on different peripheral sections of the blank.

In addition to the foregoing, the apparatus of the present invention provides a machine having a unique arrangement and construction of parts and a mode of operation all co-ordinated in a highly novel manner. For example, the invention contemplates that the roller means be non-movable (axially of the blank) and that the rotating spindle and blank, for the working operation, be moved directly into the roller means. This is of special advantage from the standpoint of simplifying the machine construction, machine operation, savings in manufacturing and maintenance costs. This type of construction is not simply an engineering choice, so to speak, as between whether to make the rollers move or to make the spindle move, because the election of a design incorporating spindle movement involves the problem of how to effect spindle rotation while, at the same time, providing for axial movement. This problem becomes critical because it is highly desirable that the power for the movement be hydraulic, in view of the large working forces involved. Rotating hydraulic connections are highly undesirable in machines of the kind in question because with the rather high rotational speeds involved and with high unit pressure being applied for long periods of time (to effect complete working of the blank), there is a very great danger of leakage which is highly undesirable from the standpoint of maintaining feed blank rate, the blank feed rate being important for maintaining the desired extrusion rate.

30 The present invention solves the foregoing problem by a unique hydraulic piston and cylinder arrangement coupled directly to the rotating spindle and providing movement thereof but with neither the piston nor cylinder rotating.

35 The invention contemplates that the roller means comprise three roller assemblies equally spaced about the rotational axis of the spindle and that the spindle axis extend vertically so that during the working operation the rotating spindle and blank are moved upwardly into the rollers. This arrangement has several advantages, for example, in permitting simplified construction for synchronizing the rollers, i.e., that corresponding parts of the rollers occupy the same radial distances from the rotational axis of the blank and lie in the same transverse planes.

40 Furthermore, by having the rollers each located at the vertex of a triangle, there is very little, if any, unbalanced radial thrust on the spindle. This, of course, avoids any tendency of the spindle to buckle and is highly desirable from the standpoint of maintaining dimensional accuracy. Furthermore, the spindle has a symmetrical construction so that the center of gravity is located along its rotational axis and, therefore, there is no radial thrust on the spindle or blank due to the forces of gravity. Also, the piston and cylinder means are arranged so that its thrust for moving the spindle lies along the rotational axis of the spindle.

45 The apparatus of the invention contemplates that each of the roller assemblies be controlled by tracer mechanism for the working operation. In the making of articles of the nature discussed, it is possible to lock each of the roller assemblies in a fixed radial position. However, the use of tracer mechanism arranged as disclosed herein has distinct advantages, particularly from the standpoint of controlling the dimensions of the articles being formed. Furthermore, in certain instances it may be desirable to form an article having a tapered wall and from this standpoint the tracer control is substantially advantageous. For tracer control the invention contemplates that each roller assembly be mounted to accommodate relative motion as between an assembly and its mount in a direction toward and away from the rotational axis of the blank. Each roller assembly has a tracer valve connected to be movable therewith and cooperating with a tracer templet or pattern which is fixed to the spindle and movable axially therewith, the templet being preferably interconnected with

the piston and cylinder means so that, while being axially movable, it has no rotary motion.

While in the foregoing I have discussed in somewhat general terms the various advantages, features and objectives of the invention, it will be apparent as the description proceeds that the invention has other highly desirable advantages and features.

The preferred manner of practicing the methods of the invention and the preferred construction of a machine for practicing the same will be apparent from the following description and drawings wherein:

FIGURE 1 is a front elevational view illustrating the general assembly of the machine;

FIGURE 2 is a plan view of FIGURE 1;

FIGURES 28 and 29 are fragmentary views of alternative roller forms.

General Description

As best seen in FIGURES 1 and 3, the machine M is supported over a pit P by the floor F and the columns C and C-1 in the pit. While the machine could be mounted so that the lowermost part thereof was suspended just above the floor level, the pit arrangement is preferred in order to reduce the overall height of the machine.

The bed of the machine comprises a main base 1 (see FIGURE 3) which has connected thereto the roller bases 2, 3 and 4. The roller bases are spaced approximately 120° apart from one another and respectively carry the roller rests 5, 6 and 7 which support the roller assemblies 10, 11 and 12. As best seen in FIGURE 3, the main base is apertured as indicated at 13 and within the aperture

is supported the spindle or spindle assembly 14 (see FIGURE 4) which is adapted to be rotated and moved along its axis of rotation which, in this instance, extends vertically. The spindle assembly carries the blank B. Connected with each of the rollers 10, 11 and 12 are tracer valves 15, 16 and 17 which cooperate with templets 20, 21 and 22 for controlling the position of the rollers with respect to the rotational axis of the blank or spindle. The templets 20, 21 and 22 are mounted on templet supports 23, 24 and 25 which are all interconnected with the spindle to be moved in a vertical direction therewith in a manner which will be explained hereinafter.

The general manner in which the machine is used is explained following. The parts are in the position as shown in FIGURES 1 and 6 and the spindle is rotated (causing rotation of the blank) and then moved vertically until such time that the rollers engage with the blank. With continued rotation and upward motion, the rollers work the blank, causing a reduction in the wall thickness thereof and the blank extrudes upwardly and away from the spindle.

The Main Base

As best seen in FIGURES 3 and 4, the main base 1 is a compartmented structure comprised of vertical cross braces 26 and annularly-shaped horizontal braces 30, 31 and 32. As indicated in FIGURE 3, the base is supported at three points over the pit; for example, one corner is supported by the column C, the other corner is supported by the column C-1 and the other corner is supported by the floor as indicated at 29. The three annular braces 30, 31 and 32 form the aperture 13 referred to heretofore. Within the aperture 13 is a spindle housing 33 which at the top rests on the brace 30 and on the side is supported laterally by the inwardly facing edges of the braces 30, 31 and 32. On the bottom of the spindle housing is an annular-shaped lower bearing housing 34 and on the lower bearing housing is a piston support 35 which, as indicated in FIGURE 1, extends down into the pit P. The cross sectional shape of the piston housing will be seen from an inspection of FIGURE 15. All of the parts just described are all rigidly tied together by conventional bolting means to make a strong unified structure.

Roller Bases

Each of the roller bases 2, 3 and 4 are substantially identical in structure and include vertically extending braces 40 as indicated in FIGURE 3 for the roller base 2. Each roller base is bolted to the main base.

The Roller Rests

Each of the roller rests is identical in construction and the description will be principally in connection with the roller rest 5 as shown in FIGURES 7 and 8. The roller rest has a main slide 41 by means of which the rest is mounted on top of the roller base 2. The roller rests are adapted to be adjustably moved toward and away from the rotational axis A of the spindle for purposes of setting up the machine for blanks of various diameters. For guiding this movement and for preventing any twisting movement of the roller rest during the working operation, there are cooperating guideways in the form of abutting shoulders on the main slide of the rest and the roller base; for example, see in FIGURE 6, the shoulders 46 and 47 on the main slide of roller rest 7 and the shoulders 48 and 49 on the roller base 4. Similar abutting shoulders for the roller base 2 and roller rest 5 are indicated at 50—50' and 51—51' in FIGURE 8.

The roller rest is adapted to be adjustably moved as described following. In FIGURE 7 a nut 52 is attached to the bottom of the slide 41 and this cooperates with a screw 53 mounted in the bracket 54 secured to the base 2. The screw is mounted so that it can be rotated but not moved axially. The screw may be manipulated by a wrench or the like applied to the head 55. While it is not

shown, the roller base 2 may be provided with grooves on its top surface to receive hydraulic fluid forced into the grooves by appropriate pumping apparatus. This has the effect of lubricating or lifting the rest away from the base so that the same can be easily adjusted by means of the screw 55.

After the roller rest has been set to an adjusted position, it may be locked in adjusted position as described following. The shoulders 50 on the base carry clamp plates 60 and 61 and the shoulders 51 of the base carry clamp plates 62 and 63. These clamp plates are arranged so that when the same are tightened down they engage the shoulders 50' and 51' on slide 41 and exert a large force to hold the rest against movement and particularly against backward tilting movement. To insure against outward movement of the rest, the notches 64 and 65, cut in the plates 61 and 63, cooperate with lock plates 66 and 70 fixed to the slide 41.

As best seen in FIGURE 2, the turnbuckle assemblies 71, 72 and 73 are connected to and extend between the respective roller rests. The turnbuckles rigidly tie the roller rests together and are for preventing outward movement and tilting of the roller rests during a working operation. The turnbuckles are adjustable to provide for radial adjustment of the roller rests as mentioned above.

The main slide 41 has a top cover 74 and these form a central aperture in the slide as indicated at 75 in FIGURE 7. In vertical cross section the aperture is generally rectangular in shape as indicated for the aperture 75' of the roller rest 7 shown in FIGURE 6. Within this aperture is disposed the roller assembly.

The roller assembly 10 is slidably mounted on the roller rest to accommodate relative motion between the assembly and the rest in a direction toward or away from the rotational axis of the blank, this relative motion being controlled by the tracer valve 15 and the cooperating templet 20. The manner of mounting the roller assembly for such movement will next be explained.

The sides of the slide 41 within the aperture are provided with a pair of guideways such as the ways for the roller rest 7 indicated at 76 and 77 in FIGURE 6. Within the guideways of the slide 41 is disposed a cradle slide 78 which in plan has a U-shaped cross section as indicated in FIGURE 8. The relative motion as between the cradle slide and the guideways is controlled by a piston and cylinder arrangement described following. The slide 41 and the top cover 74 (FIGURE 7) carry a cylinder adapter 80 which mounts a cylinder body 81. On one end of the cylinder body there is a cylinder end cover 82 and on the other end there is an end cover 83. These elements form the cylinder 84 within which is disposed the piston 85. The piston 85 has a piston rod comprising an enlarged section 86 and a reduced section 87 which is attached to the cradle slide 78. Also attached to the piston is an arm 90 carrying an adjusting nut 91. The nut 91 is used in set-up purposes, particularly in determining the innermost position of the roller assembly 10.

The conduits 92 and 93 are for the supply of fluid for the cylinder 84 so as to effect back and forth movement of the piston or to permit back and forth movement of the cylinder while the piston remains fixed as will be explained later.

Secured to the cradle slide 78 is a cradle 94 which is arcuate in shape and has an arcuate guideway 95, the axis of the guideway lying in a plane which contains the rotational axis of the spindle. As seen in FIGURE 8, on either side of the guideway are two slots 96 and 97. Mounted on the cradle is a swivel 100 which is also arcuate in shape conforming to the shape of the cradle and has a portion 101 which extends into the guideway 95. The swivel carries a segmental part of a worm wheel 102 which cooperates with a worm 103 mounted on the cradle. The swivel also carries a plurality of T-bolts 104, the heads of which cooperate with the slots 96 and 97. When the T-bolts are tightened up, the swivel is held tightly

on the cradle. When the bolts are loosened, the worm 103 can be rotated by a wrench applied to the head 105 which causes the swivel to move along the cradle. The purposes of the swivel adjustment will be explained shortly.

5 The roller assembly 10 is mounted on the swivel and arcuately movable therewith. The roller assembly has a housing 106 which abuts the swivel and is fixed thereto by means of bolts such as the bolts 107 for the roller assembly 12 as shown in FIGURE 6. The roller assembly is arranged to be adjusted in a vertical direction by means of the nut 110 which is fixed to the swivel and a screw 111 cooperating with threads in the housing 106. The key 112 which is disposed in ways on the swivel and cradle guide this vertical adjustment. The vertical adjustment is for placing corresponding parts of the roller assemblies in the same horizontal planes.

Roller Assembly

Each of the roller assemblies is identical in construction and the explanation of this will be principally in connection with the roller assembly 10 which is shown in some detail in FIGURES 7, 12, 13 and 14.

20 The housing 106 of the roller assembly mounts a pair of upper and lower bearing caps 115 and 116 which are secured to the housing by means of the screws 120 (see FIGURE 12). Bearing caps 115 and 116 support the covers 121 and 122. Within the assembly there is a roller shaft 123 being rotatably supported by means of the inboard bearings 124 and 125, and outboard bearings 25 126 and 127, the bearings 124 and 125 being disposed between the shaft and the caps, and the bearings 126 and 127 being disposed between the shaft and the covers. The shaft has a shoulder 130 upon which bear the several 30 rolling sections 131, the sections being held firm against the shoulder by the lock nut 132. This arrangement, together with the key 133, rigidly tie the rolling sections 35 together for rotation.

In the present embodiment the rolling sections are all 40 of identical construction having the same diameter and identically configured working tips or working surfaces. As will be apparent from FIGURE 7, the rolling sections 131 are serially spaced along the rotational axis A of the blank B and the working tips are spaced at different radial distances from this axis. As indicated heretofore, 45 the function of the rolling sections is to reduce fractional portions of the blank and, from this standpoint, may be considered as independent rollers.

The roller assembly, the swivel and the cradle are 50 arranged so that when the swivel is arcuately adjusted, the roller assembly pivots about the point 135 of the working tip of the center rolling section. Since the roller assembly pivots about the point 135, it will be seen that by different arcuate adjustments, the different roller 55 working tips can be spaced different distances from the rotational axis A. For example, in FIGURE 7 it will be seen that all of the five working tips occupy different radial distances from this axis. If the roller assembly is then adjusted, say more counter-clockwise, the top 60 rolling section will move closer to the axis while the bottom rolling section will move farther from the axis. The center rolling section, of course, does not move since the roller is pivoting about its working tip. This arcuate adjustment of the roller assembly, together with the radial 65 adjustment provided by the setting of nut 91 provides for variation in the total reduction to be taken on a blank and the degree of fractional reduction taken by each 70 rolling section and permits use of the rollers with blanks of various wall thickness. Where an even number of rolling sections are used, the pivot point for the roller should be intermediate the adjacent center rolling sections so that the pivoting effects equal but opposite motion of 75 corresponding sections on opposite sides of center.

The roller assembly is preferably mounted so that the rotational axis of the shaft 123 lies in a plane containing the rotational axis A of the spindle. Further, the

assembly is mounted so that with relative motion of the assembly as provided by the piston and cylinder 85 and 86 as mentioned above, or motion with the arcuate adjustment mentioned above, the movement of the shaft 123 is in this plane.

From an inspection of FIGURES 12 and 13 it will be seen that the housing and the bearing caps form an opening through which the working sections protrude.

The Spindle Assembly

The details of the spindle assembly will be described principally in connection with FIGURES 4, 5, 9, 10 and 11. In general, the spindle assembly comprises a section 140 for supporting the blank B, a shaft 141 which mounts the section 140 and extends down through the spindle housing 33 in the main base 1 and thence below the base where it is interconnected to the piston and cylinder assembly 142 which provides the power for moving the assembly in a vertical direction.

The blank support section 140 comprises an adapter 144 having radially extending ribs 145 which support an annular cylindrical section 146 around which is disposed the blank B, the blank being vertically supported by the shoulder 150. The adapter 144 is fixedly held on the shaft by the cap 151. The manner in which the shaft 141 is supported and rotated will be explained following.

The spindle housing 33 carries the upper bearings 152 while the lower bearing housing 34 carries the bearings 153. The bearings 152 and 153 rotatably support the spindle sleeve 154. Between the bearings 152 and 153 there is a worm wheel 155 which is drivingly interconnected to the sleeve 154. The worm wheel 155 meshes with a worm 156 which is adapted to be rotated by a motor as will be explained later. Rotation of the worm and the worm wheel causes rotation of the sleeve 154.

The sleeve 154 is interconnected with the spindle shaft in a manner to provide for rotation of the shaft 146 and also to provide for vertical movement of the shaft along its axis of rotation while the shaft is rotating. The manner in which this is done will be explained in connection with FIGURES 9, 10 and 11.

The top of sleeve 154 has an enlarged shoulder section 160 (see FIGURE 10) within which is disposed a drive bushing 161. The bushing (FIGURES 9 and 11) has a pair of oppositely disposed slots 162, 163 within which are disposed a pair of keys 164 and 165 which extend into corresponding slots in the sleeve 154. These keys drivingly interconnect the spindle and drive bushing. The drive bushing also has (FIGURE 11) four equally-spaced drivers 170 which have axially-extending keyways 171.

The spindle shaft 141 has four equally-spaced driving tongues 172 each having a key 173 which mates with the corresponding keyways 171. This arrangement provides for a driving interconnection between the drive bushing and the spindle shaft. From an inspection of FIGURE 4 it will be seen that the tongues 172 extend substantially the height of the main base 1. If the spindle shaft is moved in a vertical direction it will be apparent that the interconnection between the drivers 170 and the tongues 172 will provide a driving (rotational) interconnection while at the same time permitting the shaft to be moved in a vertical direction either up or down.

The piston and cylinder arrangement for moving the spindle assembly up and down will next be explained.

As best seen in FIGURE 4, the spindle shaft 141 is provided with an axially extending bore 175 within which is disposed the cylinder body 176 having end caps 180 and 181. These elements form a cylinder 182. Near the bottom of the cylinder there is an annular load collar 183 which provides a support for upper and lower bearings 184 and 185 mounted in the housing 186 rigidly connected to the spindle shaft. On the bottom or web 187 of the piston support 35 is mounted the piston rod

188 on the top of which is the piston 190. As will be apparent the rod and piston extend into the cylinder 182.

With reference to FIGURE 5 it will be seen that a chamber 191 is in communication with the bore 192 formed on the piston rod 188. The bore 192 is connected to a fluid line 193. The chamber 194 is in communication with a radially extending passage 195 formed in the rod 188 which, in communication with the annular bore 196, is also formed in the rod. The annular bore 196 is in communication with a fluid line 197. The fluid lines 193 and 197 are for conducting fluid to and from the cylinder.

When fluid is entering the chamber 191 and leaving the chamber 194, the cylinder 182 moves up. Since the spindle shaft 14 is connected to the load collar 183 of the cylinder via the housing 186 and bearings 184, the spindle shaft also is moved up. When fluid flow to the chambers 191 and 194 is reversed, the cylinder moves down, its downward motion being transmitted to the spindle shaft via the load collar 182, bearings 185 and housing 186. The manner in which fluid for the chambers 191 and 194 is controlled will be explained later.

As mentioned above, the piston 190 and its rod 188 are fixed to the piston support 35 and cannot rotate. The cylinder 182 is also held non-rotatable even though it provides the thrust for and moves vertically with the rotating spindle. The manner in which this is done will be explained in connection with FIGURES 15 and 16. The piston support 35 has three equally-spaced, vertically-extending rods 200 which are fixed to the support and disposed in openings 201 in the support. These rods carry bushings 202 which preferably are the roller bearing type, and connected to the bushings are the rod brackets 203 which are integral with or connected to the end cap 181 of the cylinder 182.

As will be apparent, the above construction provides that the bushings, rod brackets and cylinder are movable upwardly and downwardly while at the same time providing for the brackets, hence the cylinder, to be non-rotatable with the bearings 184 and 185 permitting the spindle shaft to rotate relative to the cylinder.

The above-described structure has several important advantages. For example, the cylinder being recessed in the bore in the spindle shaft, the load collar on the cylinder and the bearing between the load collar and spindle shaft all cooperate in reducing the overall length or height of the spindle assembly. Furthermore, the described arrangement eliminates the need for rotating the hydraulic fitting and/or for a rotating piston or cylinder and this makes fluid leakage minimal which is highly desirable from the standpoint of making positive control for the spindle and blank movements. Additionally, the spindle assembly has a symmetrical construction so that its center of gravity lies along its axis of rotation. Further, the thrust of the piston and cylinder 142 for moving the spindle lies along the axis of rotation.

Supports for Tracer Templets

In the preferred arrangement of the invention the spindle assembly and blank move axially into the rollers whose radial position is controlled by tracer mechanism comprising tracer valves interconnected to the rollers with the templet connected to and movable with the spindle assembly. The manner in which the templet is mounted to be movable with the spindle will be explained principally in connection with FIGURES 6, 15 and 16. All of the templet supports are identical in construction and only the templet support 25 will be mentioned in detail.

As seen in FIGURE 6, a bushing support bracket 204 is fixed to the roller base 4 at the points 205, 206 and 207 and extends upwardly adjacent the roller rest 7. The connection points lie substantially within the transverse planes of bearings 152 and 153. To this bracket are connected a pair of bushings 211 and 212 which slidably support the shafts 213 and 214. As illustrated

in FIGURE 1, the lower ends of the shafts 213 and 214 are fixed to the shaft foot 215 which in turn is fixed to the bushing 202 movably mounted on the rod 200. It will be seen, therefore, that the shafts are movable in a vertical direction with the spindle assembly but non-rotatable with respect thereto. The shafts 213 and 214 carry three supports 220, 221 and 222 which are fixed to the shafts and movable therewith. Mounted on the supports 220, 221 and 222 is a support bracket 223. The supports 221 and 222 also mount the templet support bracket 224 which in turn carries the templet 22.

From the above construction then it will be apparent that as the spindle assembly moves up and down the tracer 22 is also carried up and down and in cooperation with the tracer valve 17 controls the radial position of the roller assembly.

As will be more apparent from the description of the methods of the invention appearing hereinafter, the roller assemblies remain in fixed radial position during a working operation and the templets are arranged to obtain this condition. Templet control is preferred over locking the roller assemblies in fixed position because it has the advantage of providing for easier and more accurate roller alignment with respect to the rotational axis of the blank and in maintaining this alignment during a working operation.

The maintaining of roller alignment (or correct radial position) comes about as follows. The thrusts of the three equally-spaced roller assemblies counterbalance each other so that there is no unbalanced radial load on the spindle assembly. The spindle assembly has a symmetrical construction and the center of gravity lies along its rotational axis and thus there is no radial load or moment on the spindle due to gravity. Also, the driving torque of worm wheel 155 is imposed between the bearings 152 and 153 which minimizes any tendency for the spindle shaft to distort. Further, the thrusts of the piston and cylinder assembly 142 is centered along the axis of the spindle. The spindle assembly, therefore, is virtually distortion-free and in moving upward will carry the tracer templets upward along predetermined straight axes. Further, the bushing support bracket is connected to the roller base and not to the roller rest. Due to the direction of working thrust imposed and its construction and connection to the main base, the roller base is, for all practical purposes, distortion-free. Thus, the templet is supported on and moved by distortion-free members. Therefore, even if the roller rests should tend to move radially outwardly or to tilt, the tracer valves cooperating with the templet will cause the roller assemblies to remain in the desired radial position (the rest merely moves in or out with respect to the roller assembly).

Tracer Valve Support

Each of the tracer valves and their supports are identical in construction and the description will be in connection with the support for valve 17. As seen in FIGURES 17-19, the cradle 78 carries the tracer body bracket 230, the top cover of the rest being provided with a slot 231 to accommodate the outward extension of the tracer body bracket. As best seen in FIGURE 19, the tracer body bracket is provided with gibs 232 which cooperate with gibs 233 of the tracer valve body 234. At the opposite end of the tracer body bracket there is an adjusting screw bracket 235 in which is rotatably mounted an adjusting screw 236, the other end of the screw cooperating with a nut in the tracer valve body. By appropriately adjusting the screw, the tracer valve body can be moved back and forth. The tracer valve body supports the tracer valve 17, the stylus 17' of which cooperates with the templet 22.

Spindle Drive

The spindle drive will be explained principally in connection with FIGURES 2 and 6.

As mentioned heretofore, the spindle is driven via the worm wheel 155 and the worm 156. The worm 156 is supported on a shaft 240 mounted in bearings 241 and 242 disposed in the main base (see FIGURE 6). The shaft 240 is connected to a coupling 243 which is in turn connected to another shaft 244 mounted in the gear housing 245. The shaft 244 carries the gears 246, 250 and 251 which respectively engage the gears 252, 253 and 254 mounted on the shaft 255. The shaft 255 also carries a gear 256 which engages a gear 260 on the shaft 261. Also mounted on the shaft 244 are clutches 262 and 263, the clutch 262 interconnecting the shaft 244 and the gear 246 and the clutch 263 alternatively interconnecting the shaft 244 with the gear 250 or 251. The shaft 261 extends out of the housing 245 and mounts a pulley 264, carrying the belt 265 which is interconnected to a pulley 266 driven by a motor MTR-1.

By establishing different gear ratios with adjustments of the clutches 262 and 263, the motor MTR-1 is made to rotate the spindle assembly at several different speeds.

It will be observed that the driving torque of the worm wheel 155 is applied between the bearings 152 and 153. This arrangement is advantageous from the standpoint of minimizing spindle distortion.

25

Spindle Hydraulic

The hydraulic control for the piston and cylinder assembly 142 will be explained in connection with FIGURE 20. It will be recalled that when fluid is flowing into the chamber 191 and out of the chamber 196, the spindle assembly and blank move up. When the fluid flow is reversed, the spindle assembly and blank move down. Fluid flow for the chamber 191 is via the line 193 and fluid flow for the chamber 196 is via the line 197.

30 The line 193 incorporates a balancing valve 270 and a control valve 271 and is connected to a port 272 in the solenoid-operated valve V-1. The line 197 incorporates a control valve 273 and is connected to a port 274 on the valve V-1. The line 276 connected to port 275 connects the valve V-1 to a reservoir 280 and the line 281 connected to port 282 connects the valve V-1 to a pump 283. The pump is driven by a motor MTR-9. The valve V-1 is solenoid-operated, the solenoid SOL-3 controlling the valve for moving the spindle assembly 40 up and the solenoid SOL-4 controlling the valve for moving the spindle down. The function of the valve 270 is to balance the weight of the spindle and the function of valves 271 and 273 is to control the rate of up and down movement of the spindle.

45 When the solenoids SOL-3 and SOL-4 are de-energized the valve V-1 interconnects the ports 274, 281 and 275 so that the pump 283 pumps fluid through the line 281, through the valve V-1 and through the line 275 to reservoir.

50 When the solenoid SOL-3 is energized (with SOL-4 de-energized), the valve V-1 interconnects the ports 274 and 275 and the ports 272 and 282. Thus the fluid from the pump goes through the line 281, the valve V-1, and the control valves 271 and 270 in the line 193 to the chamber 191. The chamber 196 is connected to reservoir via the line 197, valve 273, valve V-2 and line 275. Thus with fluid flowing into the chamber 191 and out of the chamber 196, the spindle assembly moves up.

55 When the solenoid SOL-4 is energized (with SOL-3 de-energized), the valve V-1 interconnects the ports 274 and 282 and the ports 272 and 275. The fluid from the pump goes through the line 281, the valve V-1, the valve 273 in the line 197 to the chamber 196. The chamber 191 is connected to reservoir via the line 193, valves 270 and 271, valve V-1 and line 275. Thus the spindle assembly is moved down. The manner in which the solenoids SOL-3 and SOL-4 are energized will be explained hereinafter.

60 The valves 270, 271 and 273 are arranged to permit free fluid flow in the direction shown by the arrows, but

with controlled fluid flow in the opposite direction. Adjusting the valve 273 determines the rate at which fluid is metered out of the chamber 196 and hence controls the rate at which the spindle moves up. Adjusting the valve 272 determines the rate at which fluid is metered out of the chamber 191 and hence controls the rate at which the spindle moves down. By using rate control on the exhaust side, the arrangement has the advantages of providing for full unit pressure to be applied for the effecting of up and down movement.

Tracer Hydraulics

The operation of the tracer valve to position the roller assembly and/or control the motion of the roller assembly toward and away from the rotational axis of the spindle will be explained in connection with FIGURES 20 and 21 for the roller assembly 10. The roller assemblies 11 and 12 are similarly controlled.

The hydraulic system is set up so that the tracer valve can be bypassed and no longer control the roller assembly. Under this condition the roller assembly is moved all the way out or away from the rotational axis. The motion of the roller assembly is controlled by fluid supplied to the chambers 284 and 285 in the cylinder 84. It will be observed that the cross sectional area of the chamber 284 is considerably less than the cross sectional area of the chamber 285. As will be apparent, if equal unit pressures exert in each of these chambers, the piston 85 will be moved inwardly because the force acting on the piston due to the fluid in chamber 285 is greater than the force due to the fluid in chamber 284.

Before proceeding with the description of the hydraulic circuit, it is well to point out the manner in which the tracer valve 15 functions. The valve has a spool 236 comprising a central section 290 and a pair of lands 291 and 292. The spool is adapted to be moved back and forth so as to put the pressure port 293 in communication with the other ports 294 and 295. These ports are respectively connected to lines 300, 301 and 302. When the stylus 15' is undeflected, which is the position shown in FIGURE 21, the spool puts the ports 293 and 294 in communication with the land 291 covering the port 295. When the stylus is deflected, the spool moves to the left so as to put ports 294 and 295 in communication with the land 292 covering the port 293.

As shown in FIGURE 20, the line 300 is connected to a pump 303 and also interconnected to the line 92 supplying the chamber 284. The line 301 is connected to a port 304 on the valve V-2. The line 302 is connected to a drain line 305 which runs to the reservoir 306 and to a port 310 on the valve V-2. A drain line 311 in the valve 15 also runs to the reservoir 306.

The valve V-2 adapted to be actuated by the solenoids SOL-1A and SOL-2A. When the solenoid SOL-2A is energized, the tracer valve 17 is bypassed. When the solenoid SOL-1A is energized, the tracer valve controls the motion of the roller assembly. When both solenoids are de-energized, the valve V-2 sets up the system so that fluid from the pump 303 goes to reservoir.

With the solenoid SOL-2A energized (SOL-1A de-energized), the valve V-2 interconnects the ports 310 and 312 and dead-ends the port 304. Fluid from the pump 303 flows through the line 300 to the juncture *j* of the lines 300 and 92 and thence through the line 92 to the chamber 284. (Fluid cannot flow to the tracer valve 15 as will be seen by tracing the circuit—line 300, valve 15, line 301 to port 304 on valve V-2 which is dead-ended.) The chamber 285 is connected to reservoir via line 93, valve V-2 and line 305. The unit pressure in the chamber 284 causes the piston 85 to move outwardly which carries the roller assembly with it.

When the solenoid SOL-1A is energized (SOL-2A de-energized), the valve V-2 dead-ends the port 310 and interconnects the ports 304 and 312. Fluid from the pump

303 flows through the line 300 to the juncture *j* where it flows through line 92 to the cylinder 284. The fluid also flows through the tracer valve 15 and thence into the line 301, through the valve V-2, and into the line 93 to the chamber 285. While the same unit pressure exists in the cylinders, the forces on the large end are greater which tends to move the piston and roller assembly to the right. With continued motion to the right, the tracer stylus 15' contacts the pattern or templet and is deflected to move the spool 236 to the left so that the land 292 blocks off the port 293 and stops the fluid flow from the line 300 and fluid no longer flows into the chamber 285 but continues to flow via the line 92 into the chamber 284. The other chamber 285 is connected to reservoir as follows. The movement of the spool causes the land 291 to uncover the port 295 so that ports 294 and 295 are connected, hence the lines 301 and 302 are in communication. The line 302 is connected to reservoir. The line 302 is connected to line 93 via the valve V-2 so that the fluid in chamber 285 can flow to reservoir. The pressure in the chamber 284 causes the piston and roller assembly to move to the left. As soon as the stylus 15' leaves the templet, the spool moves to the position shown, the effect of which causes the roller assembly to move in as explained above. As soon as the stylus contacts the templet it causes the roller assembly to move out and so on. The actual movements, as explained above, are so small that for all practical purposes the roller assembly remains in a fixed radial position as dictated by the shape and position of the templet.

From the above description, it will be apparent that if the roller rest should tend to move away from the rotational axis of the blank, the tracer will maintain the roller assembly in the desired radial position.

When both solenoids are de-energized, the port 312 is dead-ended and the ports 304 and 310 are interconnected. Fluid from the pump 303 goes through the line 300, tracer valve 15, line 301, valve V-2 and line 305 to reservoir.

Motor Circuit

In FIGURE 23 I have diagrammatically shown how the various motors heretofore are energized. The spindle drive motor MTR-1 is interconnected to the three-phase supply lines L-1, L-2 and L-3 via the contacts 1-M-1. The spindle pump motor MTR-9 is connected with the power lines via the contacts 9-M-1. The motors MTR-11, MTR-12 and MTR-13 which drive the pumps for the tracers 15, 16 and 17 are interconnected to the power lines via the contact 11-M-1. As will be apparent, when any of the contacts 1-M-1, 9-M-1 or 11-M-1 are closed, the various motors will operate. The relay 1-M for controlling the contacts 1-M-1 is connected to the lines L-2 and L-3 via the contacts 1CR-2.

Electrical Circuits

In FIGURE 22 I have diagrammatically illustrated certain of the electric control circuits used with the apparatus described above. The manner of operation of these circuits will now be described.

On the left-hand side of FIGURE 22 there is a scale numbered (1)-(12). In the description below, to find the particular part mentioned, look to the right of the identifying number.

In FIGURE 22 (1) the transformer 315 is connected to the lines L-1 and L-2, which supply power to the lines 320, 321 and 322.

Assume first that the various components are in the position shown in FIGURE 4 with the spindle non-rotatable.

Spindle Rotated

To start the operation of the spindle, the switch 4PB (2) is depressed which picks up the relay 1CR. This relay has normally open holding contacts 1CR-1 (2) which close to hold up the relay when the switch 4PB is released. Incidentally, to stop the operation of the spindle

at any time the switch 3PB is depressed which de-energizes the relay 1CR. The normally open contacts 1CR-2 (FIGURE 23) close to energize the relay 1-M and the normally open contacts 1-M-1 close to energize the spindle motor MTR-1 which starts the spindle and blank rotating at the desired speed in a manner explained heretofore.

Tracer Pumps

To start the operation of the tracer pump 303, the switch 11PB (3) is depressed. This picks up the relay 11-M which has normally open holding contacts 11-M-1 which close to hold up the relay when the switch 11PB is released. The tracer pump may be stopped at any time by actuating the switch 10PB. With reference to FIGURE 23, the normally open contacts 11-M-1 close and power is supplied to the three tracer motors MTR-11, MTR-12 and MTR-13. The motor MTR-13 drives the pump 303 and the other motors drive similar pumps.

Roller Assembly Under Control of Tracer

To put the rollers under the control of the tracer the switch 6PB (4) is actuated which picks up the relay 2CR. The relay 2CR has normally open holding contacts 2CR-1 which close and hold up the relay when the switch 6PB is released. It will be observed that the relay 2CR is held up through the switch 7PB (5), this switch being for bypassing the tracer so that the rollers move outwardly as has been explained heretofore. Thus, at any time during the working operation that it is necessary to move the rollers out, the switch 7PB can be actuated. The relay 2CR has normally open contacts 2CR-2 and 2CR-3 (9) which close and energize the solenoids SOL-1A, SOL-1B and SOL-1C.

With reference to FIGURE 20, it will be recalled that when the solenoid SOL-1A is energized, the roller assembly 10 is put under the control of the tracer valve 15. The solenoids SOL-1B and SOL-1C are for similarly controlling the roller assemblies 11 and 12. Thus the rollers move in until such time as the stylus contacts the templet and the rollers remain in position ready for the working operation.

Referring back to the switch 7PB, when this switch is actuated, it picks up the relay 3CR and the normally open contacts 3CR-1 close to hold up the relay. Also, the normally closed contacts 3CR-2 and 3CR-3 (9) open so as to cut off power to the solenoids SOL-1A, SOL-1B and SOL-1C to prevent the operation of the tracer valves to control the roller assemblies. Further, the normally open contacts 3CR-4 and 3CR-5 (10) close to energize the solenoids SOL-2A, SOL-2B and SOL-2C. With reference to FIGURE 20, it will be recalled that when SOL-2A was energized, the tracer valve was bypassed and the roller assembly moved out. The solenoids SOL-2B and SOL-2C similarly control the roller assemblies 11 and 12.

Spindle Pump Motor

When the switch 1-SS (6) is turned to the on position, the relay 9-M is energized. Referring to FIGURE 23, the relay 9-M has normally open contacts 9-M-1 which close and energize the spindle pump motor MTR-9 which drives the pump 283.

Spindle Assembly and Blank Up

To move the spindle and blank up the switch 8PB (7) is actuated and this energizes the relay 5CR. The relay 5CR has normally open holding contacts 5CR-1 which close and hold up the relay when the switch 8PB is released. It will be observed that the hold-up circuit for the relay 5CR is through the switch 9PB (8) which is for use in moving the spindle down. Thus at any time during the working operation if it is desired to move the spindle down, the switch 9PB can be actuated. The relay 5CR has normally open contacts 5CR-2 and 5CR-3 (11) which close to energize the solenoid SOL-3. With

reference to FIGURE 22, it will be recalled that when the solenoid SOL-3 is energized, the hydraulic circuit for the spindle is actuated so as to move the spindle up.

The upward motion of the spindle carries the blank B with it which engages the three roller assemblies and the blank is worked in a manner which will be explained later.

Spindle Rotation Stopped

After the blank has been worked as desired, the spindle rotation is stopped by actuating switch 3PB (2) which de-energizes the relay 1CR. The holding contacts 1CR-1 open. The 1CR-2 contacts (FIGURE 23) open to de-energize the relay 1-M which opens the contacts 1-M-1 to de-energize the spindle drive motor MTR-1 and the spindle stops rotating.

Rollers Out

At the same time as the operator presses the 3PB switch to stop the spindle rotation, the 7PB switch (5) is actuated to start the rollers moving out. The actuation of switch 7PB (5) effects a bypassing of the tracer valves and moves the rollers out in a manner as explained heretofore.

Spindle Assembly Down

At the same time as the 3PB and 7PB switches are actuated, the operator actuates the 9PB switch (8) to stop the upward movement of the spindle and start the same moving down. When the switch 9PB is actuated, it de-energizes the relay 5CR and energizes the relay 6CR.

When the relay 5CR is de-energized, its holding contacts 5CR-1 open. Also, the 5CR-2 and 5CR-3 contacts (11) open to de-energize the solenoid SOL-3. When the solenoid SOL-3 is de-energized, the upward motion of the spindle is stopped since the supply of fluid to chamber 191 is cut off.

The relay 6CR has normally open holding contacts 6CR-1 which close to hold up the relay. The relay 6CR also has contacts 6CR-2 and 6CR-3 (11) which then open so that no power can be supplied to the solenoid SOL-3. The relay 6CR also has 6CR-4 and 6CR-5 contacts (12) which close to energize the solenoid SOL-4. With reference to FIGURE 21, it will be recalled that when the solenoid SOL-4 is energized the hydraulic system supplying the spindle assembly is set up so as to move the spindle down. When the spindle has reached its lowermost desired position, the switch 1-SS is momentarily turned to the off position so as to de-energize the relay 6CR which operates as explained above to de-energize the solenoid SOL-4.

With the rollers in the outmost position and the spindle in the down position, the finished article can be removed from the spindle and a new blank substituted therefor. Then the machine can be operated as described above for another working operation.

From the above description it will be apparent that the control of the machine is semi-automatic in the sense that the starting and stopping of the various components is under the control of the operator. It will be apparent, however, that various dogs, limit switches, etc. can be employed and certain switches added to the circuit described above so as to make the machine largely automatic in the sense that the cycle is initiated by the operator pressing a button and the various operations carried out automatically.

Methods of the Invention

In the subsequent description below I will explain the methods of the present invention and it will be understood that such methods may be practiced on apparatus such as described above which is ideally suited for the same, although it should be observed that the apparatus may be used to practice other methods, for example, when equipped with rollers having a single rolling section for reducing a blank in the conventional manner.

In FIGURE 24 I have shown a spindle 320 which is

similarly constructed to the spindle 14 described above, and supports a blank 321, the end 322 of which is abutting the shoulder 323 on the spindle and, therefore, is axially immovable. The end 324 is free to move axially away from the spindle during the working operation. A roller assembly 325 constructed along the lines of the assemblies 10, 11 or 12 described heretofore is positioned in readiness to be interengaged with the blank 321. The rotational axis of the spindle and blank is designated by 326.

The cylindrically-shaped starting blank 321 may be made in a variety of ways. For example, a rough blank having the approximate dimensions of the desired starting blank may be manufactured by casting, forging or wrapping and welding. Then the inside and outside diameters of the same are skinned or machined and the edge trimmed so that the blank has an ID for easy fitting on the spindle and wall thicknesses and length sufficient to produce the final cylinder. The dimensions of the starting blank may be calculated as follows. The dimensions and volume of the finished article are known and the starting blank must have the same volume and the same inside diameter. Knowing the strength of the material of the blank to be worked and the maximum thrust of which the machine is capable to cause relative axial motion between the blank and the rollers, a wall thickness of the starting blank which is consistent with the foregoing can be determined. Preferably the wall thickness should be such that maximum thrust need not be developed. The length of the starting blank can then be calculated by substituting the value of the wall thickness and the volume formula, the volume being that of the finished article.

With the spindle and blank rotating, the spindle is moved toward the roller assembly (or, conversely, the roller assembly is moved toward the blank) until the end 324 of the blank is engaged with the first rolling section 330. The blank is then moved at a given feed rate. The section 330 partially reduces or works the wall of the blank and causes the worked portion to extrude to the right until there is engagement between this worked portion and the rolling section 331 which then takes a further reduction and this worked portion then extrudes toward the rolling section 332 which engages the same and effects a further reduction and then this worked portion extrudes to the right for engagement with the rolling section 333 which makes another reduction and the reduced portion extrudes to the right for engagement and final reduction by the rolling section 334. With all of the rolling sections engaged with the blank, the action continues with the finally extruded portion moving continuously away from the spindle. With the roller positioned about midway on the spindle, the finally extruded or worked section 335 of the blank has moved off the spindle as shown in FIGURE 25. With continued axial motion, the roller is positioned adjacent the shoulder 323 and all of the unworked portion of the blank 336 has been reduced in thickness and elongated as is shown in FIGURE 26. The blank has now been formed into an elongated cylinder which may be removed from the spindle.

FIGURE 27 is an enlarged fragmentary view illustrating the above-described action of the roller. From an inspection of FIGURE 27 it will be seen that the roller is oriented so that the rolling sections 330-334 respectively work or reduce the annular portions S-1 through S-5 of the blank. The rolling sections are serially spaced along the axis of the blank and the working tips occupy different radial distances from the blank axis 326. With the indicated orientation, each portion has the same thickness and each rolling section takes the same fractional proportion of the total reduction (which is the sum of portions S-1, S-2, etc.). The wall thickness of the finally reduced portion 335 is the same as that of S-1 or S-2, etc. It will be observed that the reductions take place at radially and axially spaced points on the blank or that radially

and axially spaced portions (S-1 through S-5) of the blank are simultaneously reduced.

As the section S-1 is reduced by the roller 330, the metal moves under the roller and extrudes toward the roller 331 as indicated at 340 where it is engaged with the roller 331. This reduced portion becomes part of the section S-2 which is reduced by the roller 331 and extrudes toward and is engaged with the roller 332 as indicated at 341. This reduced portion becomes part of the section S-3 which is reduced by the roller 332 and extrudes toward and is engaged with the roller 333 as indicated at 342. The reduced portion becomes part of section S-4 which in turn is reduced by the roller 333 and this reduced section extrudes toward and is engaged by the roller 334. The section S-5 then is reduced by the roller 334 into the finished article 335.

It will be apparent that discrete portions of the blank are reduced simultaneously and the work required of any rolling section is only that for reducing its associated portion. For example, the work required of roller 330 is that to reduce the portion S-1 and as this portion is reduced, its metal adds to that of portion S-2 which, insofar as roller 331 is concerned, is in effect an independent blank and the work required of the roller is that for reducing the portion S-2 and so on.

In FIGURE 27 r_1 represents the distance from the blank rotational axis to the working tip of the roller 334 and r_2 represents the radius of the spindle. The letter t represents the wall thickness of the final reduction or the finished article; i.e., difference between r_1 and r_2 as measured in a plane p normal to the axis 326 and containing the working tip of the roller 334. The portion of the blank under the working tip of the roller 334 has the required inside diameter and concentricity because it conforms exactly to the surface of the spindle and also has the desired wall thickness since it is tightly engaged between the spindle surface and the working tip which is set at the desired distance from the spindle surface. It will be seen that by maintaining the foregoing relationship in the worked part 335 of the blank as it extrudes away, it is possible to maintain dimensional accuracy; i.e., uniform wall thickness, uniform inside diameter and true axial concentricity. However, as the blank extrudes away from the spindle, there is no mechanical means preventing the blank from opening up. Obviously, if the blank opens up, the inside surface will not conform to the surface of the spindle, the wall thickness will change and the blank may be eccentric rather than concentric. As mentioned above, I have discovered that by controlling the extrusion rate, i.e., the rate at which the finally reduced portion of the blank moves away from the plane p that no opening up will take place. In general, I have discovered that the control of the extrusion rate may be obtained by effecting reduction in fractional proportions and coordinating the number and extent of the reduction with the blank feed rate and rotational speed of the blank.

It can be shown that where a roller having a plurality of rolling sections is used the extrusion rate F_n is given by the relationship

$$F_n = \frac{F}{1-n}$$

where F is the feed rate of the unworked portion of the blank (or the relative axial speed between the first rolling section and the unworked portion of the blank); and n is the percentage of reductions including the reduction under consideration. Under the same conditions, the final thickness T_n of the formed article is given by the formula $T_n = T(1-n)$, where n is the same as described above and T is the thickness of the original blank. Thus, with reference to FIGURE 27, where the feed rate of the blank is 2" per minute, there being five rollers, and each roller reducing the blank by $\frac{1}{5}$ of the initial thickness, then the extrusion rate of the portion 340 extruding away from the roller 330 will be 2.4" per minute; the extrusion rate of

the portion 341 extruding away from the roller 331 will be 3" per minute; the extrusion rate of the portion 342 extruding away from the roller 332 will be 4" per minute; the extrusion rate of the portion 343 extruding away from the roller 333 will be 6" per minute; and the extrusion rate of the finally reduced portion will be 12" per minute.

In the foregoing description it will be noted that the various rolling sections of the roller are disposed closely adjacent one another. This is the preferred arrangement because all of the extrusion rates, except the last, are less than the desired rate and, therefore, there is a tendency for these extruded portions to open up. Mounting the rolling sections closely adjacent one another minimizes this effect.

By adjusting the roller of FIGURE 27 radially and making pivotal adjustments of the same, the amount of the total reduction and the degree of the fractional reductions taken by the rolling sections can be conveniently changed for many different blank thicknesses. This is of special advantage in that it measurably enlarges the range of use of the machine from the standpoint of variation in blank thickness and reduction.

In some instances, depending upon the kind of metal from which the blank is formed, one or more rolling sections can be made to effect different fractional portions of the total reduction. For example, the first rolling section can be made of a diameter larger than the others so that it takes a greater reduction than the other rollers. This has some advantage, particularly in that a higher extrusion rate is obtained by this section with consequent higher extrusion rates for the other sections. For example, in FIGURE 28 I have shown a roller assembly 350 for working a blank 351. The rolling sections 352, 353 and 354 are each of the same diameter while the section 355 is of larger diameter than these. In this instance it will be noted that only four rollers are used. The roller 355 reduces $\frac{1}{6}$ of the original thickness, while the other rollers reduce $\frac{1}{6}$ of the original thickness. In calculating extrusion rates the same principles as explained above are applied. For example, assume that the feed rate is 2.0" per minute and that the first roller takes a reduction equal to $\frac{1}{6}$ of the initial thickness, then the extrusion rate of the portion 356 will be

$$\frac{2}{1-\frac{1}{6}} = 3''$$

per minute. The extrusion rate of the portion 357 will be

$$\frac{2}{1-\frac{1}{6}} = 4''$$

per minute. The extrusion rate of the portion 358 will be

$$\frac{2}{1-\frac{1}{6}} = 6''$$

per minute. The extrusion rate for the final portion 359 will be

$$\frac{2}{1-\frac{1}{6}} = 12''$$

per minute.

The invention may be practiced by a roller having rolling sections which are each of different diameter. For example, in FIGURE 29 the blank 360 is worked by the roller assembly 361. The rolling sections 362, 363, 364 and 365 have an increasing diameter as illustrated. In this particular arrangement the rollers are set so that their rotational axis 366 is parallel to the axis of the blank and the rollers are configured and arranged so that each roller takes the same percentage reduction. While this described arrangement may be used, it has one disadvantage in that all of the rollers must be precision ground with respect to each other requiring different tool set-ups, whereas in the roller assemblies wherein the diameters of the rolling sections are all alike, a single tooling or grinding set-up can be used.

In the methods described above, the metal of the blank is displaced or distorted and consequently strain hardening takes place. Strain hardening increases the strength properties of the formed cylinder over those of the starting blank, for example, a doubling of the tensile strength. The methods disclosed herein provide a means for closely regulating the strength properties, for example, the hardness and stiffness may be developed to any degree desired within the limits of the metal being worked. Control may be effected by the number of reductions and by the extent of the working thrust or blank feed rate.

I claim:

1. The method of forming an elongated, cylindrically-shaped article comprising the steps: supporting and rotating a cylindrically-shaped blank on a spindle having an outside diameter the same as the desired inside diameter of the article, the spindle supporting the blank so that one end is axially immovable and the other end is free to move; rotating the blank and the spindle; while using a roller comprised of a plurality of rolling sections, each of the same diameter, and all fixed together for rotation about an axis, the roller axis being oriented with respect to the blank rotational axis so that the rolling sections are serially spaced along the blank axis and occupy different radial distances from the blank axis and with the angle of tilting being away from said restrained end, causing relative axial motion between the roller and blank to engage said free end with the first of said rolling sections, continuing said relative motion until all of said sections are in engagement with said blank, the rolling sections effecting simultaneous reductions of axially and radially spaced portions of the blank while controlling said relative motion, said blank rotational speed and the number of said reductions to control the extrusion rate of the final of said reductions so that the dimensions of the inside diameter and the wall thickness of the formed article are the same as those of the blank at the final reduction.

2. In a machine tool: a bed including a roller base; a spindle for supporting a blank to be worked; means mounting the spindle on the bed for rotation about a generally vertical axis and for movement along its rotational axis; a roller rest mounted on said base; tracer template support means and a template movably mounted on said base; mechanism connecting said support means and said spindle and providing for the support means to be movable axially with the spindle but without rotation; a cradle having a sliding connection with said roller rest, the connection providing for relative motion between the cradle and the roller rest in a direction toward and away from said axis and the cradle being formed with an arcuate guideway; a tracer valve connected with said cradle and cooperating with said template; a swivel mounted on said cradle and having a portion extending into said guideway; means to move said swivel along said guideway; a roller comprising a plurality of rolling sections serially spaced along said axis mounted on said swivel; the roller and the swivel being constructed and arranged whereby motion of the swivel along the guideway effects a pivoting of the roller to dispose the working tips of said rolling sections different radial distances from said axis.

3. In a machine tool: a bed formed with a central aperture and including a plurality of roller bases symmetrically arranged about said aperture; a plurality of roller rests respectively disposed on said bases; a plurality of rollers mounting assemblies respectively mounted on said roller rests, each assembly carrying a roller with the axis of rotation of each roller extending generally vertically; a spindle assembly adapted to rotate about a vertical axis and including a blank support disposed above said aperture and interjacent said rollers and a spindle shaft extending downwardly through said aperture; a drive bushing rotatably mounted on said bed within said aperture; means to rotate said bushing; key and keyway means inter-

connecting said drive bushing and said shaft and providing for rotation of the shaft and for movement of the shaft while rotating along its axis of rotation; cylinder means adapted to be moved along said axis; means including bearings interconnecting said cylinder means and said shaft and providing for rotation of the shaft with respect to the cylinder and for vertical movement of the shaft with the cylinder; piston means fixedly connected with said bed and extending into said cylinder; means to prevent rotation of said cylinder; and mechanism to control fluid to said piston and cylinder means to move said cylinder.

4. In a machine tool: a bed; a spindle assembly mounted on said bed and including a blank support and a spindle shaft; a plurality of rollers on said bed symmetrically disposed around the axis of rotation of said spindle; a drive bushing rotatably mounted on said bed within said aperture; means to rotate said bushing; key and keyway means interconnecting said drive bushing and said shaft and providing for rotation of the shaft and for movement of the shaft while rotating along its axis of rotation; cylinder means adapted to be moved along said axis; means including bearings interconnecting said cylinder and said shaft and providing for rotation of the shaft and for movement of the shaft while rotating along its axis of rotation; cylinder means adapted to be moved along said axis; means including bearings interconnecting said cylinder and said shaft and providing for rotation of the shaft and for movement of the shaft with the cylinder; piston means fixedly connected with said bed and extending into said cylinder; means to prevent rotation of said cylinder; and mechanism to control fluid to said piston and cylinder means to move said cylinder.

5. In a machine tool: a bed; a roller on said bed; a spindle assembly mounted on said bed and including a blank support and a shaft; a drive bushing rotatably mounted on said bed; means to rotate said drive bushing; key and keyway means interconnecting said drive bushing and said shaft providing for rotation of the shaft and for movement of the shaft while rotating; cylinder means adapted to be moved along the axis of rotation of said spindle; means including bearings interconnecting said cylinder and said shaft providing for rotation of the shaft and for movement of the shaft with the cylinder; piston means fixedly connected with said bed and extending into said cylinder; means to prevent rotation of said cylinder; and mechanism to control fluid to said piston and cylinder means to move said cylinder.

6. In a machine tool: a bed; a roller mounted on said bed; a rotatable spindle assembly including a blank support and a spindle shaft, the shaft being formed with a bore extending along the rotational axis of the assembly; means mounting said shaft on said bed and providing for rotation of the shaft and to be movable along its axis of rotation while rotating; cylinder means disposed in said bore and adapted to be moved along said axis; means including bearings interconnecting the cylinder means and the shaft and providing for the shaft to be rotatable and for the shaft and cylinder to be movable together along said axis; piston means fixed on said bed and extending into said cylinder; means to prevent rotation of said cylinder including a sliding connection accommodating movement of the cylinder along said axis; and mechanism controlling fluid to said piston and cylinder means to move the cylinder.

7. In a machine tool: a bed; a roller mounted on said bed; a rotatable spindle assembly including a blank support and a spindle shaft, the shaft being formed with a bore extending along the rotational axis of the cylinder; cylinder means disposed in said bore and adapted to be moved along said axis; means mounting said shaft on said bed and providing for the shaft to be rotatable and to be movable while rotating along its axis of rotation; mechanism interconnecting the cylinder means and the shaft and providing for the shaft to be rotatable and for the shaft and cylinder to be movable together along said axis; a piston support connected to said bed; guide means connected between said support and said cylinder including a sliding connection preventing the cylinder from rotating and accommodating axial movement of the cylinder; piston

means fixed on said bed and extending into said cylinder; and mechanism controlling fluid to said cylinder and piston means to move the cylinder.

8. A construction in accordance with claim 7 wherein said guide means comprises a rod on said piston support and an arm fixed on said cylinder and slidably connected to said rod.

9. In a machine tool: a bed; a roller mounted on said bed; a rotatable spindle assembly including a blank support and a spindle shaft; means mounting said shaft on said bed and providing for the shaft to be rotatable and to be movable while rotating along its axis of rotation; cylinder means adapted to be moved along said axis; means including bearings interconnecting the cylinder means and the shaft and providing for the shaft to be rotatable and for the shaft and cylinder to be axially movable together; piston means fixed on said bed and extending into said cylinder; means to prevent rotation of the cylinder including a sliding connection accommodating axial movement of the cylinder; and mechanism controlling fluid to said piston and cylinder means to move the cylinder.

10. In a machine tool: a bed; a roller mounted on said bed; a spindle for mounting a blank to be worked; means mounting said spindle on said bed and providing for the spindle to be rotatable and to be movable while rotating along its axis of rotation; means to rotate said spindle; means including piston and cylinder elements to move said spindle along its axis of rotation, one of said elements being fixed on said bed; mechanism connecting the other of said elements to said spindle, including bearing means to accommodate relative rotation of the spindle and other element and thrust means providing for the other element to move the spindle; means to prevent rotation of said other element including a sliding connection accommodating axial movement of the other element; and mechanism controlling fluid to said piston and cylinder elements to move said other element.

11. In a machine tool: a bed; a roller element on said bed; a spindle element on said bed for mounting a blank to be worked; mechanism interconnecting said elements including means providing for rotation of one of said elements about an axis and for movement while rotating along said axis; means including a piston device and a cylinder device to move said one element along said axis, one of said devices being fixed on said bed; mechanism connecting the other of said devices to said one element including bearing means to accommodate relative rotation of said one element and said other device and thrust means providing for said other device to move said one element; means to prevent rotation of said other device including a sliding connection accommodating axial movement of said other device; and mechanism controlling fluid to said piston and cylinder devices to move said other device.

12. In a machine tool: a bed formed with a centrally located, vertically extending aperture; an annular spindle housing inside of said central aperture and fixed to said bed; first thrust bearings on the top of the spindle housing; a spindle sleeve mounted on said thrust bearings; a bearing housing on said spindle housing at the lower end of the aperture; second thrust bearings between the spindle sleeve and said lower bearing housing, each of said thrust bearings rotatably mounting said spindle sleeve; a drive gear for rotating said sleeve and connected to said sleeve between said bearings; a drive bushing fixed to the top of the spindle sleeve; a plurality of drivers on said bushings each having a keyway; a spindle shaft in said sleeve having an axial bore on one end; a plurality of driving tongues on the top end of said spindle each having a key respectively mating with said keyways, the key and keyway providing for rotation of the spindle shaft with rotation of the sleeve and for axial movement of the shaft while rotating; a cylinder inside of the said bore; a load collar on the lower end of the cylinder; third and fourth thrust bearings on opposite sides of said collar; a bear-

ing housing surrounding said third and fourth bearings and secured to said spindle shaft, the bearings providing for rotation of said shaft with respect to said cylinder; a hollow piston support extending down from said spindle housing; a piston on said support and extending upwardly into said cylinder; rod means extending upwardly in said piston support; a bracket connected to said cylinder and extending radially outwardly and slidably engaged with said rod means, the sliding connections preventing the cylinder from rotating and accommodating upward movement of the cylinder and bracket; and mechanism to control fluid to said piston and cylinder to move the cylinder.

13. In a machine tool: a bed; a spindle assembly including a blank support and a spindle shaft, the assembly being rotatable and movable along its rotational axis; a plurality of rollers respectively mounted on said bed for movement toward and away from the rotational axis of said spindle assembly, the rollers being symmetrically disposed about said axis; a plurality of fluid operated mechanisms on said bed for respectively controlling said movements of said rollers; a plurality of tracer mechanisms each including a tracer valve respectively connected with the rollers, the tracer mechanisms being for controlling said fluid operated mechanisms; means mounting said shaft on said bed and providing for the shaft to be rotatable and to be movable along its axis of rotation while rotating; mechanism mounted on said bed and connected with said spindle shaft for moving the same along its axis of rotation; cylinder means adapted to be moved along said axis; bearing means interconnecting said cylinder means and said shaft and providing for the shaft to be rotatable with respect to the cylinder and for the shaft and cylinder to be axially movable together; piston means fixed on said bed and extending into said cylinder; mechanism to prevent rotation of said cylinder including a sliding connection accommodating movement of the cylinder along said axis; a plurality of templates each mounted on said bed for movement in a direction generally parallel said axis and connected with said cylinder, the templates respectively cooperating with said tracer valves; and mechanism controlling fluid to said piston and cylinder means to move the cylinder.

14. In a machine tool: a bed; a rotatable spindle assembly including a blank support and a spindle shaft, the assembly being rotatable and movable along its rotational axis; a roller mounted on said bed for movement toward and away from the rotational axis of said spindle assembly; fluid operated means on said bed for controlling said movement of said roller; tracer mechanism including a tracer valve connected to said roller, the tracer mechanism being for controlling said fluid operated means; means mounting said shaft on said bed and providing for the shaft to be rotatable with respect to the bed and to be movable while rotating along its axis of rotation; cylinder means adapted to be moved along said axis; bearing means interconnecting said cylinder and said shaft and providing for the shaft to be rotatable with respect to the cylinder and for the shaft and cylinder to be axially movable together; piston means fixed on said bed and extending into said cylinder; means to prevent rotation of said cylinder including a sliding connection accommodating movement of the cylinder along said axis; a template mounted on said bed for movement in a direction generally parallel said axis and connected with said cylinder, the template cooperating with said tracer valve; and mechanism controlling fluid to said piston and cylinder means to move the cylinder.

15. In a machine tool: a bed; a spindle for supporting a blank to be worked; means mounting said spindle on said bed for rotation and for movement along its axis of rotation while rotating; mechanism on said bed and connected with said spindle for rotating the same;

mechanism on said bed and connected with said spindle for moving the same along its axis of rotation; a tracer template mounted on said bed for motion in a direction generally parallel said axis; mechanism connecting said template with said spindle and providing for said template to be moved axially with the spindle, but without rotation; a roller for working a blank mounted on said spindle; a slide mounting said roller on said bed and providing for relative motion between the bed and the roller in a direction toward and away from said axis; piston and cylinder means connected between said bed and said slide to control said relative motion; and a tracer valve mounted on said slide and cooperating with said template for controlling fluid for operating said piston and cylinder means.

16. In a machine tool: a bed; a spindle for supporting a blank to be worked; means mounting said spindle and said bed for rotation and for movement along its axis of rotation while rotating; a template mounted on said bed for movement in a direction generally parallel to said axis; mechanism interconnecting said template and said spindle and providing for the axial movement of the spindle to move the template; a roller for working a blank mounted on said spindle; means mounting said roller on said bed and providing for relative motion between the roller and the bed in a direction toward and away from said axis; control mechanism to control said relative motion; means connected with said roller and cooperating with said template to operate said control mechanism.

17. In a machine tool: a bed; a spindle for supporting a blank to be worked; means mounting said spindle on said bed for rotation and for movement along its axis of rotation; means mounted on said bed and connected with said spindle for rotating the same; means connected between said bed and said spindle for moving the spindle along its axis of rotation; a plurality of rollers symmetrically disposed about said axis; a plurality of tracer templates, one for each roller, each movably mounted on said bed for movement in a direction generally parallel said axis; mechanism connecting said templates and said spindle and providing for each template to be axially movable with said spindle; a plurality of slides, one for each roller, each slide mounting a roller on said bed and providing for relative motion between the bed and its roller in a direction toward and away from said axis; piston and cylinder means, one for each slide, connected between said bed and a slide to control said relative motion thereof; and a plurality of tracer valves, one for each slide, each valve being mounted on a slide and cooperating with the corresponding template for controlling fluid for operating the corresponding piston and cylinder means.

18. In a machine tool: a bed including a plurality of roller rests each respectively mounting a roller, the rollers being symmetrically spaced about a vertical axis; a spindle for mounting a blank to be worked; mechanism including bearing means disposed below said roller rests and rollers and mounting said spindle on said bed for rotation about said axis and for movement along said axis while rotating and the center of gravity of said spindle lying substantially in said axis; mechanism mounted on said bed and connected with said spindle for rotating the same; fluid operated mechanism connected between said bed and said spindle for moving the spindle along said axis, the thrust of said fluid operated mechanism lying substantially in said axis; a plurality of tracer templates, one for each roller; connections between said templates and said bed providing for movement of the templates in a direction generally parallel said axis; means connecting each template with said spindle and providing for simultaneous movement

of the templates with said spindle, but without rotation; a plurality of slides, one for each roller, respectively mounted on said roller rests and providing for relative motion between its roller and roller rest in a direction toward and away from said axis; a plurality of 5 piston and cylinder means, one for each roller, respectively connected between a roller rest and a slide for controlling said relative motion; and a plurality of tracer valves, one for each slide, each respectively mounted on a slide and cooperating with the corresponding template 10 for operating the corresponding piston and cylinder means.
